UNITED STATES PATENT OFFICE.

WILLIAM RANDALL PHILLIPS, OF TRENTON, NEW JERSEY.

NON-REFILLABLE BOTTLE.

SPECIFICATION forming part of Letters Patent No. 634,184, dated October 3, 1899.

Application filed November 28, 1898. Serial No. 697,674. (No model.)

To all whom it may concern:

Be it known that I, WILLIAM RANDALL PHILLIPS, a citizen of the United States, residing at Trenton, in the county of Mercer and State of New Jersey, have invented new and useful Improvements in Non-Refillable Bottles, of which the following is a specification.

My invention relates to non-refillable bottles; and its object is to provide an improved construction of the same whereby the bottle after having once been filled and the contents emptied cannot be again refilled without detection.

It is also an object to provide improved means for securing the stopper in place in the bottle which can be used as a corkscrew to remove the cork when desired.

The invention consists in the novel construction and combination of parts hereinabove fully described and claimed.

In the accompanying drawings, Figure 1 is an elevation of so much of a bottle as is necessary to show my improvements. Fig. 2 is a longitudinal section of the same. Fig. 3 is a plan view. Fig. 4 is a perspective view of the upper portion of the neck of the bottle, the stopper being removed. Fig. 5 is a similar view of the stopper removed from the bottle.

In the said drawings the reference-numeral 1 designates the neck of the bottle, of any ordinary or suitable construction, formed with the usual reinforcing or strengthening boss or flange 2 at the mouth thereof. This boss or flange is provided with diametrically opposite recesses in the lower end thereof. Located in these recesses and formed integral with the bottle are nibs or hooks 4, at each side of which are grooves 5, extending to the top of the boss and their lower ends intersecting the said recesses.

The numeral 6 designates the stopper, consisting of an ordinary cork, which is inserted in the mouth of the bottle.

The numeral 7 designates a corkscrew consisting of a single piece of wire, one end of

which is twisted into spiral form and engaged with the stopper after the manner of an ordinary corkscrew. The other end of the wire is then bent into a loop 10 and the end brought down and connected with the said spirally-twisted portion. The said end is driven sufficiently far into the cork or stopper to prevent a tool being inserted beneath the same so as to disconnect it from the spiral portion. The said loop is then bent down upon the cork or stopper and then carried downward along opposite sides of the stopper and engaged with the nibs or hooks 4. The wire above the lower ends of the nibs or hooks will engage with the grooves 5. When a bottle is filled and the stopper driven into the mouth thereof, the said loop will engage with the nibs or hooks and the spring or expansion of the stopper will hold the said loop securely in engagement with said nibs. To withdraw the contents of the bottle, the nibs or hooks are broken off, so that the loop is disengaged. The loop is pulled out or extended, as seen in Fig. 5, so that it will serve as a handle to remove the stopper from the bottle.

Having thus fully described my invention, what I claim is—

The combination with the bottle having a boss or flange at the mouth formed with diametrically opposite recesses at the lower end and the nibs located in said recesses provided with grooves at the sides intersecting said recesses and extending to the top of the bottle, of the stopper, the corkscrew connected therewith provided with loops extending down the sides of the bottle and engaging with said nibs, substantially as described.

In testimony whereof I have hereunto set my hand in presence of two subscribing witnesses.

WILLIAM RANDALL PHILLIPS.
